AUTOMOBILE HOOD ORNAMENT

Dean B. Hammond, Ann Arbor, and Robert Cadwallader, Detroit, Mich., assignors to Kaiser-Frazer Corporation, Willow Run, Mich., a corporation of Nevada

Application March 29, 1949, Serial No. 1,694

Term of patent 14 years

(Cl. D14—18)

To all whom it may concern:

Be it known that we, Robert Cadwallader and Dean B. Hammond, both citizens of the United States, residing in the city of Detroit, county of Wayne, and State of Michigan, and the city of Ann Arbor, county of Washtenaw, and State of Michigan, respectively, have invented a new, original, and ornamental Design for an Automobile Hood Ornament, of which the following is a specification, reference being had to the accompanying drawing, forming a part thereof.

Figure 1 is a top plan view of an automobile hood ornament showing our new design;

Fig. 2 is a side elevational view thereof;

Fig. 3 is a front elevational view thereof, taken from the left of Fig. 2; and

Fig. 4 is a rear elevational view thereof, taken from the right of Fig. 2.

We claim:

The ornamental design for an automobile hood ornament, as shown.

DEAN B. HAMMOND.
ROBERT CADWALLADER.
